Shaledig Incubator for Hatching Egg, site visited [Nov. 29, 2025]. Available from Internet. URL: <https://www.amazon.com/Shaledig-Incubator-Hatching-Automatic-Humidity/dp/B0F6MMX923> (Year: 2025).*

Primary Examiner — T Chase Nelson*Assistant Examiner* — Kelly L Gross(74) *Attorney, Agent, or Firm* — All West Law Group PLLC; Aaron Powell(57) **CLAIM**

The ornamental design for an incubator, as shown and described.

DESCRIPTION

FIG. 1 is a top, front, right side perspective view of an incubator, showing my new design;

FIG. 2 is a bottom, rear, right side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The evenly dashed broken lines illustrate portions of the incubator and form no part of the claimed design.

1 Claim, 8 Drawing Sheets
